ADJUSTABLE AIR BLAST HEATER FOR LOCOMOTIVES

Application filed January 18, 1930. Serial No. 421,837.

This invention relates to new and useful improvements in adjustable air blast heaters for locomotives.

It is one of the principal objects of our invention to provide for the fire boxes of locomotives, an adjustable air blast device.

Another object of our invention is to provide means controlled by a lever in the cab of the engine for moving the air blast device 10 to its proper position within the fire box for a heavy or a shallow fire.

By supplying heated air to the top of the coal as required, fuel economy, better combustion, less smoke, and other advantages 15 result.

Other important and incidental objects will be brought out in the following specification and particularly set forth in the subjoined claims.

20 In the accompanying drawings illustrating our invention, Figure 1 is a longitudinal sectional view taken through a locomotive fire box, showing our adjustable air blast tubes and raising means therefor. Figure 2 is a lateral section taken through the same. Figure 3 is a plan view thereof. Figure 4 is a longitudinal sectional view taken through one of the air blast tubes. Figure 5 is a top plan view of one of said tubes. And 25 Figure 6 is a bottom plan view thereof.

Referring to the accompanying drawings illustrating our invention, the numeral 1 designates a conventional locomotive fire box containing a series of grate bars 2. Each 30 grate bar is formed at its ends with cylindrical projections 3, 3 which are received by semi-circular depressions in through bars 4 secured to the ends of the fire box 1. Projecting downwardly from the central portions of the grate bars 2 are arms 5 that are pivotally connected at their lower ends to a longitudinally movable bar 6. The latter is secured at its outer end to an operating lever 7 fulcrumed on a bracket 8 secured to the fire box.

35 A shaker bar (not shown) is adapted to be applied to the lever 7 for the purpose of oscillating the grates 2 to release the ashes from the fire bed 9 upon them. (See Figures 1 and 2.)

For the purpose of supplying heated air to the top of the fire bed 9 to promote the proper combustion of the fuel thereon, and thereby to obtain great fuel economy and heating efficiency, with less smoke, we provide the following adjustable air blast device. On each side of the central through bar 4 the adjacent edges of some of the grate bars 2 are formed at their middle portions with oppositely disposed semi-circular recesses 10 to provide holes through which vertically adjustable air tubes 11 project. Although we show six of these tubes in the accompanying drawings, a greater or less number of them may be provided according to the cubic capacity of the fire box.

Each tube 11, which is constructed of suitable metal, is formed with a conical or other pointed head 12. (See Figures 4 and 5.) Such a head permits the tube to be 40 easily projected through the fire bed.

Formed in each tube 11 immediately below its top circular edge 13 are radial air holes 14 which project heated air laterally over the top surface of the fire bed 9. These 45 holes are formed in the sides of the tubes 11 for the purpose of better promoting the combustion of the fuel, since air discharged vertically from them would tend to pass upwardly without imparting much oxygen to the fire.

On the lower end of each tube 11 there is a disc bottom 15 formed with a central hole 16 and two oppositely disposed semi-circular side holes 17, 17. (See Figures 4 and 6.) Projecting upwardly through the hole 16 in the bottom of each tube 11, is an axial air pipe 18, which discharges air under pressure into the tube. The lower ends of the pipes 18 are connected below their respective tubes 11, to a sectional, horizontal supply tube 19.

The section 20 of the tube 19, being farthest from the operating end of the device, is of smaller diameter than the section 21, which is connected to a flexible steel air supply tubing 22 of still larger diameter. (See Figure 1.) This tubing 22 is connected to an air compressor (not shown) for supplying air under pressure to the tubes 23.

11 that are raised and lowered by the following means.

Referring to Figures 1 and 2, there is secured to the lower ends of the three tubes 11 in each long row, a flat connecting bar 23. Above the latter there is connected to both ends of the lower portion of the fire box 1 a fixed guide 24 containing holes 25 through which the tubes 11 freely project. (See Figures 1 and 4.)

Each connecting bar 23 is formed with two horizontal slots 26, 26, one on each side of the central tube 11. Projecting through the right hand slot 26 from an inclined bar 27 is a pin 28. The outer end of this bar 27 is hingedly connected by a pin 29 to a bracket member 30 secured to the front wall of the lower portion of the fire box 1.

Formed in the free end of the bar 27 is a longitudinal slot 31 which receives a double washered pin 32 that also passes through a similar slot 33 in the lower inclined end of a lever 34. Projecting into the left hand slot 26 of the connecting bar 23, from the slotted end of the lever 34, is a pin 35, which, like the pin 28, has secured to it two washers 36 to properly guide the pin, without friction, in its longitudinal movement through the slot.

The lever 34 is fulcrumed on a pin 37 secured to a bracket 38 on the lower portion of the fire box 1. The outer part of the lever 34 is bent upwardly for projection into the cab (not shown) above it for operation by the fireman.

When the fireman exerts an outward pull upon the upper end of the lever 34, which crosses in scissor fashion the bar 27, both the latter and the lower end of the lever 40 will raise the connecting bar 23 through their slot and pin connection to it. The elevation of the bar 23 will in turn raise the tubes 11 to a level where air will be discharged laterally from the holes 14 upon the fire bed 9. This air comprises that which is delivered under pressure into the tubes 11 by the pipes 18, and atmospheric air which is drawn into said tubes by suction through the holes 17 in their bottom portions 15.

In its passage through those portions of the tubes 11 which are in direct contact with the fire bed 9, the air introduced to the fire bed is heated, but not to a degree where it 55 will lose its power to promote the complete combustion of the gases in the fire box.

Being under pressure, which can be varied, the air that enters the tubes 11 from the air compressor can be increased or diminished according to the fuel required for the generation of steam.

The height of the apertured top portions of the tubes 11 above the fire bed 9 can also be easily varied by the lever 34 to promote 60 the proper combustion of the fuel. If the

tubes are too low or too high, the air discharged from them will not be properly distributed to the fuel bed for complete combustion.

Our adjustable air blast device prompts a fireman to evenly distribute the green coal over the surface of the grates, since if he covers up one or more of the tubes 11 with a large bank of coal, a thorough combustion of it will not take place. This is due to the fact that the hydrocarbon gases in banks of coal to which the air supply is reduced, will be distilled off.

Therefore, it behoves a fireman, if he desires to reduce his labor and at the same time obtain a clean hot fire, to so distribute the coal over the surface of the grates that all of the tubes will project a uniform distance above the fuel bed, whereupon banks that result in uneven firing will not be formed.

By promoting at all times a thorough combustion of the fuel in the fire box, our device insures a thin, clean fire from which no black smoke or clinkers result.

Our air blast means are particularly advantageous when the locomotive is mounting a grade, since additional air can be introduced to the fire bed at the beginning of the grade by a further opening of the air compressor valve. By operating the lever 34 at the same time, the tubes 11 can be raised a proper distance above the level of the additional coal added to the fire to evenly distribute the additional air to it. Thus, it is possible to maintain a uniform steam pressure at all times, with a clean, clear fire, that is intensified or lessened according to the grades encountered. This also results in fuel economy and the prevention of smoke.

Having described our invention, we claim:

1. In a locomotive fire box including a series of grate bars mounted adjacent each other to support a bed of fuel, tubes formed with air discharge holes in their upper ends, vertically movable through said grate bars and fuel bed, lever means for adjusting said tubes to bring their air discharge ends a desired distance above the fuel bed, and means for delivering air under pressure to said tubes.

2. In a locomotive fire box including a series of grate bars mounted adjacent each other to support a bed of fuel, tubes formed with air discharge holes in their upper ends, vertically movable through said grate bars and fuel bed, means for delivering air under pressure to said tubes, a horizontal bar connected to the lower ends of said tubes, and a lever pivotally secured to said bar for raising said tubes in unison to bring their air discharge ends a desired distance above the fuel bed for the purpose specified.

3. In a locomotive fire box including a

series of grate bars mounted adjacent each other to support a bed of fuel, tubes formed with air discharge holes in their upper ends, vertically movable through said grate bars and fuel bed, means for delivering air under pressure to said tubes, a horizontal bar connected to the lower ends of said tubes, a pair of members pivotally secured to said fire box, said members being slidably connected to each other at their free ends and to the connecting bar at their middle portions, and a lever handle extension on one of said members.

4. In a locomotive fire box including a series of grate bars mounted adjacent each other to support a bed of fuel, tubes formed with air discharge holes in their upper ends vertically movable through said grate bars and fuel bed, means for delivering air under pressure to said tubes, a horizontal bar connected to the lower ends of said tubes, a pair of inclined rods pivotally secured to said fire box, said rods having a slot and pin connection at their free ends below the connecting bar with which they also have a slot and pin connection, and a lever handle extension on one of said bars.

In testimony whereof we have hereunto set our hands this 16th day of January, 1930.

OSCAR H. STONE,
DAVID A. COOPER.
